Application April 9, 1951, Serial No. 219,912
In Great Britain April 12, 1950

21 Claims. (Cl. 66—89)

1

The present invention relates to straight bar knitting machines and is especially applicable to straight bar knitting machines for the production of fashioned fabrics as for example full fashioned ladies stockings.

In machines of this type different mechanisms such as, for example, adjusting devices or lead screws for adjusting the thread carrier travel and the movement of narrowing fingers, control drums and other control mechanisms, have to be actuated intermittently as is well known in straight bar knitting machines.

In this specification the term intermittently actuated mechanism is used to denote a mechanism which is adjusted in position in a step-by-step manner at regular or irregular intervals. The normal way of intermittently actuating these mechanisms is by means of ratchets and pawls in connection with levers controlled by cams and cam followers. A disadvantage of pawl and ratchet mechanisms is that during racking movements performed at high speed the kinetic energy of the ratchet and the parts connected with it, has to be dealt with at the end of the racking motion by a brake or other suitable means. This makes a pawl and ratchet mechanism which is to work safely at a high speed rather complicated.

The object of the present invention is to provide knitting machines of the type set forth with intermittently operating driving means for safely actuating the intermittently adjusted mechanisms referred to above.

According to the present invention a straight bar knitting machine is provided with at least one driving device for a lead screw or other control device in which a driving member is engageable with a driven member in such a manner that the angular velocity of the driven member is first increased from zero, or from a very low value, to a maximum and then reduced again to zero, or to a very low value.

According to a further feature of the invention a straight bar knitting machine has a drive for an intermittently actuated mechanism, which drive includes a rotatable driven member having a plurality of slots extending inwardly from the periphery thereof and being equi-spaced therearound, a constantly rotating driving member bearing at least one pin slidably carried thereon,

and means for slidably displacing a pin for selectively engaging the driven member.

A driving device according to one embodiment of the present invention may consist of a slotted disc rotatable about a given axis and a pin or a set of pins movable in a circular path about another axis (preferably at right angles to the first mentioned axis) and capable of being displaced, whilst moving in said circular path, in the direction of said second axis for engagement and disengagement with said slotted disc. The axial displacement of said pin or pins, which extend radially of said second axis, may be controlled by a profile element or cam capable of being moved into and out of the circular path of said pin or pins. The pins may be of varying height so that a selected number of them may engage and displace the disc by movement of the profile element or cam by a selected extent into the path of travel of the pins. By using two rows of pins and two profile elements or cams on opposite sides of the disc, the disc may be turned in one direction or the other.

In one form of construction the slotted disc is in the form of a Maltese cross pivoted about an axis perpendicular to the axis of the driving member, which may consist of a drum having transverse slots in its periphery each containing a slide bearing a radially extending pin at or near each end thereof, the position of the Maltese cross being such that the rows of pins may normally pass one on each side of the Maltese cross without engaging it. Two profile elements or cams which may be in the form of profiled metal strips or plates are arranged above the path of travel of the pins, one on each side of the cross, so as to be individually raised and lowered into the respective paths of the pins. Thus when one cam is lowered it will engage a pin on one side of a slide to draw the other pin of that slide into engagement with the Maltese cross. A second cam or a second pair of cams may be arranged in the path of the pins to withdraw each pin from engagement with the Maltese cross and to restore it to its original axial position after it has turned the Maltese cross through a given angle.

The pins may be of varying height so that a greater or lesser number of pins may be brought into engagement with the Maltese cross by a

greater or lesser movement of a profile element or cam towards the pin carrying drum.

It will be appreciated that in the arrangement described above the Maltese cross may be angularly displaced in one direction or the other by appropriate manipulation of one or other of said profile elements or cams and may be moved to a greater or lesser extent according to the extent of the movement of the profile element.

In another embodiment the slotted disc is in the form of a Maltese cross and is rotatable about an axis parallel to the axis of the driving member which may consist of a disc having one or more radially extending slots each one containing a slide bearing a pin extending longitudinally parallel to the axis of the driving member, the position of the Maltese cross being such that a pin normally passes along a circular path on one side of the Maltese cross without engaging it. For this purpose one end of each pin may be caused to travel along an arcuate groove. A second groove may be provided in the region of the Maltese cross to guide the pin so that whilst it is rotated with the driving member it is also displaced radially so as to be brought into engagement with the Maltese cross. A profile insert or gate may be provided at the junction of the second and circular grooves so that a pin may be guided selectively into the second groove for engagement with the driven member. With the driving member continuously rotated in one direction the Maltese cross may be driven step-wise preferably in the opposite direction, and selective actuation of the intermittently actuated mechanism in one direction or the other may conveniently be obtained by inserting a reversible gear transmission between the Maltese cross and the intermittently actuated mechanism.

The Maltese cross driving device is in itself not novel as a mechanism, but it has not so far been applied to the actuation of control elements of a straight bar knitting machine. Moreover, the present invention provides a Maltese cross driving device which may be selectively engaged at appropriate times to cause displacement of an intermittently actuated mechanism in one direction or the other and to cause displacement of different amplitudes.

The present invention will now be further described with reference to the accompanying drawings which show by way of example embodiments of the invention and in which:

Fig. 1 is an elevation showing one embodiment of the invention,

Fig. 2 is a plan view shown in section along the line II-II of Fig. 1,

Fig. 3 is a plan view shown in section along the lines III-III in Figs. 1 and 6.

Fig. 4 is a diagrammatic developed view indicating the actual and relative movements of certain parts of the present invention,

Fig. 5 is a plan view in the direction of arrow A in Fig. 1 with certain parts omitted for the sake of clarity,

Fig. 6 is an elevation of a second embodiment of the present invention showing additional features of this invention,

Fig. 7 is a diagrammatic view showing the application of the present invention for the operation of certain movements of a straight bar knitting machine,

Fig. 8 is an end elevation showing diagrammatically another embodiment of the present invention, with certain parts removed for the sake of clarity.

Fig. 9 is an end elevation of the embodiment of the present invention shown in Fig. 8 as seen in the direction of arrow B in Fig. 8, and

Fig. 10 is a detail view to an enlarged scale of part of the embodiment shown in Fig. 8.

Referring particularly to Figs. 1, 2 and 3, a drum 2 mounted on a continuously rotating shaft 1 carries one or more slides 3. The slides 3 are equally spaced over one part of the circumference of drum 2 as indicated by the reference x, while the remaining part of its circumference as indicated by the reference y carries no slides. The slides 3 extend parallel to the axis of shaft 1 and are individually slidably carried in slots at or near the circumference of the drum 2. Each slide 3 carries in a radial direction two pins 4 and 5, all of equal length and spaced exactly alike on all slides. Covers 6 hold slides 3 in their slots in drum 2, allowing them to slide in a direction parallel to the axis of shaft 1.

A bracket 7 carries rotatably a shaft 8, arranged with its axis at an angle to shaft 1, preferably in such a way that its axis intersects the axis of shaft 1 more or less at right angles. Shaft 8 supports at its lower end between bracket 7 and drum 2 a slotted disc 9 and above bracket 7 and contacting its upper face, a locating disc 10, both parts being attached to shaft 8 in a way to impede any axial movement of shaft 8.

In holes bored substantially parallel to the centre line of shaft 8 in bracket 7 are slidably supported four pins 13, 14, 15 and 16, two of which for example 13 and 15, hold at their lower ends a movable profile element or curve 11, while the remaining two, 14 and 16, hold at their lower ends another movable profile cam or curve 12. Attached to bracket 7 and located underneath curves 11, 12, but above slotted disc 9, is a fixed profile element or curve 20. Extensions 17 and 18 on the upper ends of pins 13 and 14 respectively engage the forked ends of levers 26 and 27, which are rotatably supported on a shaft 25 in bracket 7. The upper ends of levers 26 and 27 are connected by means of connecting rods 19 and 20 respectively to any of the well known control mechanisms for straight bar knitting machines thereby enabling the curves 11, 12 to be individually and separately brought from their inoperative position as indicated in full-line into their operative position 11a, 12a as indicated by chain-dotted lines in Fig. 1.

Supported from bracket 7 and free to oscillate around a shaft 28 is a locating lever 29, a wedge-shaped extension of which can, under the influence of a tension-spring or other suitable means 127, be brought into contact with V-shaped grooves on locating disc 10. This locating disc 10, and locating lever 29 serve to make sure that slotted disc 9 is held in a position to clear pins 4 and 5 during the normal performance of the knitting machine during which no racking movement takes place. In this position of the locating disc 10, slots 23 and 24 in slotted disc 9 are so orientated as to allow pins 4 and 5 to engage slotted disc 9 at the beginning of any racking movement without causing undue shocks.

The paths of movement of pins 4 and 5 both in space and in relation to slotted disc 9 are more particularly indicated in Fig. 4. In the normal knitting operation, during which no racking movement occurs pins 4 and 5 follow circular paths as indicated by full-lines 30 and 31 respectively. During this operation movable profile elements or curves 11 and 12 are held in their

inoperative position and pins 4 and 5 clear the outer edge of slotted disc 9.

During part of the revolution of shaft 1 while that part of drum 2 indicated by the reference *y* passes underneath slotted disc 9, movable curve 11 may be brought into its operative position 11a under the influence of lever 26 and connecting rod 19, while movable curve 12 remains in its inoperative position. During the further rotation of shaft 1 and drum 2, pin 4 or pins 4, engage movable curve 11 and are caused to follow a path as indicated by chain-dotted line 32 in Fig. 4. Pins 5 correspondingly follow the path indicated by chain-dotted line 33 in Fig. 4 engaging slot 23 in slotted disc 9 without undue shock, turning slotted disc 9 for one-quarter of a revolution for each of pins 5 engaging slotted disc 9, and leaving slot 23 in a more or less radial direction. It is obvious that the movement of pins 4 and 5 will cause slotted disc 9 and shaft 8 to perform one-quarter of a revolution in the direction of chain-dotted arrow 36 in Fig. 4 for each of the pairs of pins 4 and 5 slideably supported in drum 2.

In order to achieve a rotation of slotted disc 9 and shaft 8 in the opposite direction as indicated by dotted arrow 37 in Fig. 4, movable curve 11 is held in its inoperative position while movable curve 12 is brought into its operative position 12a under the influence of lever 27 and connecting rod 20. In this position of the movable curves 11 and 12, pin 5 contacts curve 12 causing pins 4 and 5 to follow a path as indicated by dotted lines 34 and 35 respectively. Pin 4 or pins 4 engage slot 24 in slotted disc 9 causing slotted disc 9 to perform one-quarter of a revolution for each of pins 4 that are brought into engagement with slots 24. Pins 4 leave slot 24 in slotted disc 9 at the end of each quarter of a revolution in a more or less radial direction along the centre line of slot 24.

It is essential that pins 4 and 5 be well guided without much clearance between the protruding parts of movable curves 11 and 12 and reset parts 21 and 22 of fixed curve 29 in order to achieve a substantially shock-free engagement and disengagement of pins 4 and 5 with slots 24 and 23 respectively in slotted disc 9 and in order to prevent any over-racking of slotted disc 9 and shaft 8 even at very high speeds.

An additional feature of the present invention is indicated in Fig. 6, the general arrangement being the same as described above. Movable profile elements or curves 39 can each be brought into three different positions which are: their inoperative position 39a, their first operative position 39b, and their second operative position 39c. Drum 2 on shaft 1 carries on its circumference over that part indicated by the reference character *u* in Fig. 6, pairs of pins 40, 41 each of a length enabling them to engage movable curves 39 in their first and second operative position as indicated in full-line in Fig. 6. Another part of drum 2 indicated by the reference character *v* in Fig. 6 carries pairs of pins 42, 43 which are shorter than pins 40, 41 by an amount indicated at 44 in Fig. 6 causing them to engage movable curves 39 in their second operative position only as indicated by chain-dotted lines 39b in Fig. 6. This feature of the present invention makes it possible to achieve two different racking movements in each direction.

More than two amounts of racking in each direction can be achieved easily by providing drum 2 with three or more different lengths of pins and

by arranging movable curves 39 and their controls in such a way as to enable them to be brought into a corresponding number of operative positions.

- 5 A second embodiment of the invention will now be described with reference to Figs. 8, 9 and 10. A shaft 81 continuously rotating in the direction of arrow C in Fig. 8 carries fixedly a disc 82 on which are mounted one or a plurality of radially slideable slides 83 equally spaced over part of its circumference. Each of the slides has attached to it a projection such as a pin 84 extending from one side thereof in a direction substantially parallel to the axis of shaft 81.
- 10 15 Friction means 85, or any other suitable stop-mechanism restrains unintended movement of slides 83 in a radial direction.

- Supported from the main frame of the knitting machine is a guide-plate 86 in which are formed 20 a more or less V-shaped groove 88, 89, an entry part 87 and a circular-part 90. A swinging plate or gate 91, attached to a shaft 92, is supported in guide-plate 86 and is free to oscillate round the axis of shaft 92. A groove machined into the 25 swinging plate or gate 91 is arranged in the path of pins 84, in such a way as either in one position to close the entrance to groove 88, or, in another position 91a to cause pins 84 to enter groove 88.
- 30 35 40 45 A slotted disc 97 is fixed to a shaft 96 rotatably supported in guide-plate 86 in such a manner that two of four slots 98 is slotted disc 97 coincide with grooves 88 and 89 in guide-plate 86. Concave parts 99 of slotted disc 97 are shaped to contact and engage a stop-plate 100, attached to disc 82 behind the slide 83, or behind the last of the slides 83, in the direction of rotation of disc 82 and shaft 81. Fixed to shaft 96 on the opposite side of guide-plate 86 is a bevel gear 115 50 55 engaging two bevel gears 116 and 117 rotatably supported on a shaft 119, which is freely carried in extensions of guide-plate 86 in such a manner that its axis intersects the axis of shaft 96.

- Slidably keyed to shaft 119 is a clutch member 45 50 55 60 65 70 75 80 85 90 95 100 105 110 115 120 125 130 135 140 145 150 155 160 165 170 175 180 185 190 195 200 205 210 215 220 225 230 235 240 higher than cam stud 113, causes cam-follower 94 to contact cam 104.

During the normal performance of a straight-bar knitting machine during which shaft 119 is to be kept stationary, cam follower 94 is in its inoperative position as indicated in Fig. 9. Swinging plate or gate 91 closes the entrance to groove 88 so as to cause all pins 84 to follow a circular path as indicated by chain-dotted line 101 in Fig. 8. Control chain 112 is racked by any conventional means well known in the design of straight-bar knitting machines.

When movement of the control chain causes cam stud 113 to contact bell-crank lever 110, cam-follower 94 is brought into contact with cam 103 which is shaped in such a manner as to cause swinging plate or gate 91 to be brought into its operative position 91a to cause one or a predetermined number of pins 84 to enter into the groove 88 and follow a path as indicated by dotted line 102 in Fig. 10, so as to drive slotted disc 97 through one-quarter of a revolution in the direction of arrow D for each pin 84 that is brought into groove 88.

Cam stud 114 on control chain 112 is higher than cam stud 113 in order to bring cam-follower 94 into contact with cam 104. Cam 104 is shaped in such a manner as to cause a predetermined number or all of the pins 84 to enter groove 88 and to turn slotted disc 97 through an angle other than that caused by cam 113 contacting lever 110.

Each rotation of slotted disc 97 in the direction of arrow D in Fig. 10 causes a rotation of shaft 119 through a corresponding angle in the direction of arrow E in Fig. 10.

In order to rotate shaft 119 in a direction opposite to arrow E in Fig. 10, cam 127' is brought into contact with bell-crank lever 129 thereby causing clutch member 118 to be disengaged from bevel gear 116 and to be engaged to bevel gear 117. Control drum 124 is racked at predetermined intervals by any of the conventional racking mechanisms well known in the design of straight bar knitting machines.

One of many applications of the present invention to a straight bar knitting machine will now be described with reference to Fig. 7 which shows by way of example the inclusion of the embodiment shown in Figs. 1, 2 and 3. A constantly rotating shaft 45 which may preferably but not necessarily be the main cam shaft of the machine is rotatably supported in bearings 49 in the main frame of the knitting machine and is rotated by an electric motor or other prime mover 48 by means of a gear transmission 46 and 47. One or more shafts 52 are rotatably supported in bearings on the main frame of the knitting machine and connected to shaft 45 by means of bevel gears 50 and 51 which cause shafts 52 to take part in any rotary movement of shaft 45. Each of shafts 52 carries one or more drums 53 each of which has slideably supported parallel to the axis of shafts 52 one or more slides 54 carrying pairs of pins 55. A bracket 59 supported from the main frame of the knitting machine above each and every drum 53, carries rotatably a shaft 57 substantially at right angles to shaft 52 so that the centre lines of the shafts 52 and 57 intersect. A slotted disc 56, a locating disc 58 and a bevel gear 73 are fixed on shaft 57 to rotate therewith. The upper end of shaft 57 is guided by a bearing 72 supported from the main frame of the knitting machine. A lead screw 74 is supported in bearings 75 and 76 and fixedly carries at its end a

bevel gear 80 engaging bevel gear 73 on shaft 57. The threaded part of lead screw 74 carries a spindle nut 77 which might, for example, be arranged to limit the stroke of thread carrier rods 78 carrying thread carriers 79.

Pivots supported on bracket 59 is a locating lever 69 engaging locating disc 58 to hold shaft 57 and slotted disc 56 in their normal position ready to be engaged by pins 55 in drum 53.

Equally supported on bracket 59 in a way as described above, is a fixed curve 62 and a pair of movable curves 61 which are normally held in their inoperative position as indicated in Fig. 7, and which can be brought into their lower or operative position or positions each under the influence of one of a pair of bell-crank levers 63. These bell-crank levers are individually connected by connecting links 64 to levers 65 rotatably supported on a shaft 66 in the frame of the knitting machine. A control drum 67 can be racked by a cam 71 attached to shaft 45 by means of a cam follower 70, suitable connecting means and a racking mechanism 69. Control cam studs 68 are arranged on control drum 67 in suitable places in tracks underneath each lever 65 so as to cause the corresponding movable curve 61 to be selectively brought into its operative position and thereby resulting in rotation of shaft 57 and lead screw 74 through a pre-selected amount in a predetermined and desired direction during rotation of shaft 45 and drum 53.

The application of the present invention is, however, not restricted to the racking of the lead screw controlling the stroke of the thread carrier rods but it may equally well be applied to the racking of the lead screw controlling the splicing stops, the racking of the lead screw controlling the position of the narrowing points, the racking of any control shafts or control drums, and for any other intermittently operated movement in a straight bar knitting machine.

I claim:

1. In a straight bar knitting machine embodying at least one adjustable control such as a lead screw or narrowing finger control, a driving means for said control device including a rotatable driven member having a plurality of slots extending inwardly from the periphery thereof and equi-spaced therearound, a constantly rotating driving member bearing at least one projection such as a pin slideable thereon and means for slideably displacing at least one such projection from a normal position in which during the rotation of the driving member it will not engage the driven member into a position thereon at which it will engage a slot of the driven member and means for subsequently restoring said projection to its normal position.
2. In a knitting machine according to claim 1 a driven member having four equally spaced slots.
3. In a knitting machine according to claim 1 a driven member having slots therein extending radially in relation to the axis of rotation of the driven member.
4. In a knitting machine according to claim 1, a driven member which is rotatable about an axis other than the axis of rotation of the driving member.
5. In a knitting machine according to claim 1, a driven member rotatable about an axis which intersects the axis of the driving member at right angles thereto.
6. In a straight bar knitting machine embodying at least one adjustable control such as a lead screw or narrowing finger control, a driving means

for said control device including a rotatable driven member having a plurality of slots extending inwardly from the periphery thereof and equi-spaced therearound, a driving member constantly rotating about an axis substantially at right angles to the axis of rotation of the driven member, at least one projection, such as a pin, extending substantially radially outwardly from said driving member and slideably mounted thereon to permit slideable displacement thereof in a direction substantially parallel to the axis of rotation of the driving member and means for controllably sliding said projection from a normal position in which during the rotation of the driving member it will not engage the driven member into a position thereon at which it will engage a slot on the driven member and means for substantially restoring said projection to its normal position.

7. In a straight bar knitting machine embodying at least one adjustable control such as a lead screw or narrowing finger control, a driving means for said control device including a rotatable driven member having a plurality of slots extending inwardly from the periphery thereof and equi-spaced therearound, a driving member constantly rotating about an axis substantially at right angles to the axis of rotation of the driven member, at least one projection, such as a pin, extending substantially radially outwardly from said driving member and slideably mounted thereon to permit slideable displacement thereof in a direction substantially parallel to the axis of rotation of the driving member, a displaceable profile means for slideably displacing at least one such projection from a normal position in which during the rotation of the driving member it will not engage the driven member into a position thereon at which it will engage a slot on the driven member, and fixed profile means for subsequently restoring said projection to its normal position.

8. In a knitting machine according to claim 7, at least one profile element or cam movable into and out of a circular path of said projection and when in such circular path to cause said axial displacement of said projection.

9. In a knitting machine according to claim 7 a stationary profile element or cam lying adjacent the normal circular path of said projection and adapted to restore said projection to its normal position after it has been displaced into a position at which it will engage the driven member.

10. In a knitting machine according to claim 7 a plurality of projections such as pins slideably mounted on said driving member and cam means controlling the movement of said profile element for the selective displacement of one or more of said projections.

11. In a knitting machine according to claim 10 in which at least certain of said projections are of differing height so that a selected number thereof may be caused to move into engagement with the driven member by movement of said profile element by a predetermined extent into the path of travel of said projections.

12. In a knitting machine according to claim 7, a driving member bearing two rows of projections normally adapted to pass one row on either side of the driven member and two sets of profile elements associated respectively with said rows of projections and adapted to be slideably displaced into the paths of said projections in order to bring about their engagement with the slotted

driven member to cause rotation thereof in one direction or the other.

13. In a straight bar knitting machine according to claim 1, resilient detent means for holding said driven member stationary after each adjustment thereof.

14. In a straight bar knitting machine according to claim 7, resilient detent means for holding said driven member stationary after each adjustment thereof.

15. In a straight bar knitting machine embodying at least one adjustable control such as a lead screw or narrowing finger control, a driving means for said control device including a rotatable driven member having a plurality of slots extending inwardly from the periphery thereof, and equi-spaced therearound, a driving member constantly rotating about an axis substantially parallel with the axis of rotation of said driven member, at least one projection such as a pin borne by said driving member and slideable thereon in a substantially radial direction, guide means adjacent to said driven member defining alternative paths of travel for said projection one of which paths causes the projection not to engage the driven member and the other of which causes the projection to be brought into engagement with a slot of the driven member and subsequently to be withdrawn from said slot, and a gate for directing the projection on to one or other of said paths.

16. In a knitting machine according to claim 15, a guide means for said projection having two merging grooves formed therein, one of said grooves being of arcuate form and the other of said grooves diverging outwardly from said first mentioned groove and subsequently returning thereto.

17. In a knitting machine according to claim 15, a reversible transmission gear between the driven member and the control device to permit actuation of the control device in either direction.

18. In a knitting machine according to claim 15, a plurality of projections on said driving member, a pattern chain, and a link and lever mechanism operated by the pattern chain for controlling said gate to determine the number of projections to be moved into engagement with the driven member and thus to determine the extent of movement of the driven member.

19. In a knitting machine according to claim 18, a reversible transmission gear between the driven member and the control device to permit actuation of the control device in either direction.

20. In a straight bar knitting machine embodying at least one adjustable control such as a lead screw or narrowing finger control, a driving means for said control device including a rotatable driven member having a plurality of slots extending inwardly from the periphery thereof, and equi-spaced therearound, a driving member constantly rotating about an axis substantially parallel with the axis of rotation of said driven member, at least one projection such as a pin borne by said driving member, extending in a direction substantially parallel to the axis thereof, and slideable thereon in a substantially radial direction, guide means adjacent to said driven member defining alternative paths of travel for said projection one of which paths causes the projection not to engage the driven member and the other of which causes the projection to be brought into engagement with a

11

slot of the driven member and subsequently to be withdrawn from said slot, and a gate for directing the projection on to one or other of said paths.

21. In a straight bar knitting machine embodying at least one adjustable control such as a lead screw or narrowing finger control, a driving means for said control device including a rotatable driven member having a plurality of slots extending inwardly from the periphery thereof and equi-spaced therearound, a constantly rotating driving member bearing at least one projection such as a pin slideable thereon in a substantially radial direction in relation to the axis of rotation of the driving member and means for slideably displacing at least one such projection

10

from a normal position in which during the rotation of the driving member it will not engage the driven member into a position thereon at which it will engage a slot of the driven member and means for subsequently restoring said projection to its normal position.
